UNITED STATES PATENT OFFICE.

CHARLES FREDERICK CRAIG, OF SAN FRANCISCO, CALIFORNIA, ASSIGNOR TO CRAIG GOLFMETER CO., OF WILMINGTON, DELAWARE, A CORPORATION OF DELAWARE.

CAPTIVE-BALL PRACTICE DEVICE.

1,421,414.

Specification of Letters Patent. Patented July 4, 1922.

Application filed July 19, 1921. Serial No. 485,806.

To all whom it may concern:

Be it known that I, CHARLES FREDERICK CRAIG, a citizen of the United States, residing at the city and county of San Francisco and State of California, have invented certain new and useful Improvements in Captive-Ball Practice Devices, of which the following is a specification.

My invention relates to that class of captive-ball practice-devices in which the blow delivered to the ball rotates a member, the motion of which is transmitted to a register arranged to indicate, in terms desired, the force and effect of the blow.

Devices of this nature, though adapted for a variety of games, are especially intended for golf-practice, in that the resultant register indication may be made to show, either directly or indirectly, the distance the ball would have traveled, under the force of the blow, if said ball had been free.

My present invention is an improvement upon that captive-ball practice device for which, jointly with Herschel M. Connor, I filed application for patent December 8, 1919, under Serial Number 343,363, which said application was allowed March 29, 1921, but the patent for which is not yet issued.

The object of my present invention is, generally, to improve the device whereby the machine is structurally more efficient, with respect to strength, durability, reliability and accuracy, and is adapted for a more satisfactory indication of the force and effect of the blow delivered.

With this object in view, my invention consists in the novel captive-ball practice-device which I shall hereinafter fully describe, by reference to the accompanying drawings, in which—

Fig. 1 is a vertical section, partly in elevation of my device, the dotted lines showing the position of the captive ball when at its maximum height, under the force of the blow.

Fig. 2 is a horizontal section, enlarged, on the line 2—2 of Fig. 1, looking in the direction of the arrows.

Fig. 3 is a longitudinal sectional detail of the captive-line slidable connection.

Fig. 4 is an enlarged sectional detail showing the adjustable connection of the register with the top of the fixed standard.

Fig. 5 is a front view, enlarged, of the

register, the dial-plate being broken in part 55 to show the driving connections.

Fig. 6 is a sectional view of the clutch mechanism for operating the hand of the register.

1 is a base adapted to be screwed or bolted 60 down upon a firm foundation. This base is formed with a central boss 2, in which is fitted a cushion 3, lined with a metallic thimble 4, the lower end of which is flanged under the base and is provided with a cross 65 bar 5. The upper end of the thimble is flanged over the top of the cushion with an intervening washer 6. See Fig. 1.

In the thimble 4 is fitted a standard 7, 70 the lower end of which is slotted over the cross bar 5, Fig. 1, whereby said standard is prevented from turning under the severe jar, necessarily following the operation of the device.

8 is a sleeve mounted for rotation about 75 the fixed standard 7. The sleeve is carried by the standard by means of a suitable bearing or bearings. In the present case there is a single bearing, preferably of the ball type. This is not shown, but is located at 80 the top of the sleeve indicated at 9, so that the sleeve is suspended by this bearing, with its bottom having clearance between it and the top washer 6 of the base 1, whereby the sleeve is made very sensitive to rotation. 85

Fixed upon the top of the sleeve is a collar 10 from which extends an arm 11 in one direction, and a second arm 12 in the opposite direction, the arm 12 carrying a counter-weight or ball 13. 90

The lower end of the sleeve is also fitted with a collar 14 from which extends an arm 15—Fig. 2.

16 is a rod which, at its upper end is preferably formed with a goose-neck bend 16', 95 the extremity of said bend being removably fitted in a socket 11' in the arm 11, and is fixed therein by a set screw 17, Fig. 1. The lower end of the rod is preferably formed with a bend 16'', the extremity of which is removably fitted in a socket 15' in the arm 15 and is set therein by a screw 18, Fig. 2. Thus the rod 16 is carried by the sleeve 8, in spaced relation thereto and extends for its full length. The bends of the rod tend 105 to reduce its rigidity, thereby affording compensation under the sudden pressure upon it, due to the force of the blow on the ball;

and the lower bend permits the initial or rest position of the ball connection to be low down, as seen in full lines in Fig. 1.

19 is a golf or other ball. The ball is connected by a flexible line 20 with the rod 16. The connection of the line 20 with the rod is a freely slideable one, a good form being here shown, Fig. 3, as an embracing yoke 21 fitted with a roller 22.

10 A stop 23, Fig. 1, is carried by the rod 16 just above its lower bend, in order to arrest the downward fall of the roller connection 21 of the ball-line 20, so that said connection shall not be caught in said bend.

15 24 is a register. This is fitted on top of the fixed standard 7, the fitting being best formed as seen in Fig. 4, by slipping it upon said standard, and adjustably holding it by a thumb-screw 25, playing in a circumferential groove 7' in the standard. Thus the register may be turned at will to conveniently face the operator.

The register is provided with a dial face 24' which may be graduated in any terms desired, preferably marked in terms of distance, the graduations being determined by and proportionate to the gear-train which operates the hand 26 playing over the dial.

30 The hand 26 is fitted upon the squared end of an arbor 27 which extends back through the register casing and has fixed upon its rear end a thumb wheel 28, Fig. 6, by means of which the arbor 27 may be manually turned to initially set or return 35 the hand.

About the arbor 27 is loosely fitted the hub 29 of a worm-wheel 30, said hub being journaled for rotation in a bearing boss 24' of the register casing.

40 Between the rear end of the worm-wheel hub 29 and the hub 28' of the thumb wheel 28 is a friction clutch disk 31 of paper or other suitable material, Fig. 6, said clutch being held operative by means of a spring 45 32 lying between the front of the worm-wheel 30 and a flange 27' of the arbor 27.

It will now be seen that by turning the thumb wheel 28, the hand may be reset without affecting the worm-wheel 30, because the 50 friction clutch may slip, but when the worm wheel is rotated, it will, through the clutch, turn the thumb wheel, and through said wheel and the arbor 27 will turn the hand.

55 Mounted in suitable bearings in the register casing is a short shaft 33, Fig. 5, the upper end of which carries a worm 34 which meshes with the worm-wheel 30. The lower end of the shaft 33 projects below the casing and carries a gear 35, which meshes with a 60 gear 36 fixed upon the upper end of the sleeve 8. It will thus be seen that by the rotation of the sleeve 8 motion will be transmitted through the gear train to the hand of the register.

65 In using the device the ball is laid upon

a mat or other support and is hit with the club in the same way that a shot would be made from the tee or in the fairway. It leaves the club with great speed, and as it rises and its captive line tautens, the line 70 connection runs up on the rod 16 and the captive ball moving in a circle rotates the sleeve 8 on the fixed standard 7. The speed of the ball is not checked and it will travel its full distance. While traveling, the hand 75 moving over the dial face records the yards of its journey. When its energy is expended, the ball falls as it would on a golf course.

It will be seen from Fig. 1 that the counterweight ball 13 is slideable on the arm 12 and is controlled by a spring 13'. This indicates a simple form of centrifugal control for the purpose of automatically equalizing the revolution of the sleeve proportionate 85 to the force of the blow, so that the sleeve will revolve smoothly and without tendency to jerk.

I claim:

1. A device of the class described, comprising a fixed standard; a sleeve adapted to revolve about said standard; a register member carried by the top of the standard above the sleeve; a rotatable shaft carried by the register member; a gear on top of the sleeve; a gear on the lower end of the shaft engaging with the sleeve gear; and means for operating the register-member from the upper end of said shaft.

2. A device of the class described comprising a fixed standard; a sleeve adapted to revolve about said standard; a register member carried by the top of the standard above the sleeve, said member having a graduated face and a hand playing thereover; an arbor carrying the hand, a rotatable shaft mounted in said register member with one end projecting therefrom; a worm on the inner end of the shaft; a gear on the outer end thereof; a worm wheel within the register member engaging the worm and associated with the hand-arbor for operating the hand; a gear on the top of the sleeve engaging the gear on the outer end of the shaft; a ball; and a connection between said ball and sleeve for rotating the sleeve when the ball is struck.

3. A device of the class described comprising a fixed standard; a sleeve adapted to revolve about said standard; a register member carried by the top of the standard above the sleeve, said member having a graduated face and a hand playing thereover; an arbor carrying the hand, a rotatable shaft mounted in said register member with one end projecting therefrom; a worm on the inner end of the shaft; a gear on the outer end thereof; a worm wheel within the register member engaging the worm and associated with the hand-arbor for operating the hand; means 130

associated with said worm-wheel and hand-arbor for resetting the hand independently of the worm-wheel; a gear on the top of the sleeve engaging the gear on the outer 5 end of the shaft; a ball; and a connection between said ball and sleeve for rotating the sleeve when the ball is struck.

4. In a device of the class described the combination of a fixed standard; a sleeve 10 adapted to revolve about said standard; a ball; a connection between said ball and sleeve for rotating the sleeve when the ball is struck; a register member fitted to the top of the standard and rotatively adjustable 15 thereon; and means for operating said register member by the rotation of the sleeve.

5. In a device of the class described the combination of a fixed standard; a sleeve adapted to revolve about said standard; a 20 ball; a connection between said ball and sleeve for rotating the sleeve when the ball is struck; a register member fitted to the top of the standard and rotatively adjustable thereon; a gear on the top of the sleeve; 25 a rotatable shaft carried by the register member to one side of the axis of rotative adjustment thereof; a gear on one end of said shaft meshing with the gear on the sleeve; and means for operating the register 30 member from the other end of said shaft.

6. In a device of the class described the combination of a base having a boss; a cushion fitted in said boss; a lining member within the cushion for holding it in the boss, 35 said lining member having an internal cross-

bar; a fixed standard fitted in said lining member with its lower end slotted upon the cross bar thereof; a sleeve revolvably carried by the standard; a register member carried by the top of the standard; means actuated 40 by the rotation of the sleeve to operate the register member; a ball; and a connection between said ball and sleeve for rotating the sleeve when the ball is struck.

7. In a device of the class described, the 45 combination of a fixed standard; a sleeve adapted to revolve about said standard; a rod carried by said sleeve in spaced relation; a ball; a connection between the ball and rod, freely slidable upon the rod; means for 50 registering the revolutions of the sleeve under the force of the blow delivered upon the ball; and a centrifugally acting device carried by the sleeve for automatically equalizing its revolution proportionate to the 55 force of the blow.

8. In a device of the class described, the combination of a fixed standard; a sleeve adapted to revolve about said standard; a 60 ball; a connection between the ball and sleeve for revolving the sleeve when the ball is struck; means for registering the revolutions of the sleeve; and a centrifugally acting device carried by the sleeve for automatically equalizing its revolution proportionate to 65 the force of the blow delivered upon the ball.

In testimony whereof I have signed my name to this specification.

CHARLES FREDERICK CRAIG.
